UNITED STATES PATENT OFFICE.

OSCAR STROMBORG, OF LOS ANGELES, CALIFORNIA.

TEMPORARY STRUCTURE AND METHOD OF FORMING SAME.

Application filed December 18, 1920. Serial No. 431,766.

To all whom it may concern:

Be it known that I, OSCAR STROMBORG, a citizen of the United States, residing at Los Angeles, in the county of Los Angeles and State of California, have invented new and useful Improvements in Temporary Structures and Methods of Forming Same, of which the following is a specification.

This invention relates to means and methods for forming temporary structures for various uses, and particularly pertains to a means for forming a structure of ice or other solidified liquids.

An object of this invention is to provide a structure which may be readily formed by freezing liquids into a body of any desired shape for the purpose of effecting temporary repairs or attachments or erecting a structure of more or less temporary character, and which is applicable for use in restricting or directing the flow of water, and in confining a liquid to hold it from flowing into areas desired to be protected until permanent changes or structures can be made, such for example, as in the raising and recovery of sunken vessels, the erection of dams, piers, docks, breakwaters, and the like, in preventing seepage in excavations, such as mines, tunnels, etc., and which may also be employed in effecting a temporary connection with surfaces as in attaching hoisting means to submerged vessels and the like and recovery of any other objects from a submerged position.

Another object is to provide a temporary structure of the above character which may be readily put in place and easily and quickly removed, and which may be designed to have the necessary strength to effect the purpose for which it is intended.

A further object is to provide a means for forming ice structures within bodies of water by which a structure may be formed at submerged points and at great depths or erected in running streams and swift currents.

Other objects of the invention and various advantages derived by its use will be realized from the examples given.

The accompanying drawings illustrate by way of example the manner of applying the invention to several uses, in which:

Figure 1 is a view in elevation with parts broken away showing a fabricated structure with refrigerating pipes therein for freezing a body of ice on the structure.

Figure 2 is a view in section as seen on the line 2—2 of Figure 1 showing the fabricated structure as submerged in a liquid previous to the refrigerating operation.

Figure 3 is a similar view showing the manner in which the completed frozen structure is formed.

Figure 4 is a plan view of a hull of a ship showing the manner of employing the invention inclosing deck openings in raising sunken vessels.

Figure 5 is a detail in vertical section illustrating the manner of closing openings in the sides of ship hulls and the like.

Figure 6 is a view in side elevation showing the manner of employing the invention in effecting connections with a ship's hull.

Figure 7 is a plan view illustrating the application of the invention to the construction of coffer-dams and the like.

Figure 8 is a view of the dam as seen in elevation.

Figure 9 is a detail cross section illustrating the manner of forming the dam.

Figure 10 is a detail vertical section as seen on the line 10—10 of Figure 9.

Figure 11 is a view in vertical section showing the application of the invention to the construction of an arch or truss.

Figure 12 is a view in section as seen on the line 12—12 of Figure 11.

Figure 13 is a view in vertical section illustrating the invention as applied in closing underground water courses to prevent seepage.

Figure 14 is a view in elevation as seen in the direction of the arrow 14 in Figure 13.

Referring to the drawings more specifically, 15 indicates a conduit of any suitable character through which any desired refrigerating medium may be passed to effect a freezing action on a liquid in which the conduit may be submerged or which may be applied thereto to form a body of ice; and 16 designates a series of reinforcing members here shown as comprising rods which are arranged adjacent to the conduit, but which may consist of any desired construction or material and arrangement of reinforcing elements as occasion may require.

The conduit 15 and the reinforcement 16 may be formed into a structure of any desired size and shape according to the purpose for which it is to be employed. Various relative arrangements of the conduit and

- the reinforcement may be used. Extending over the outer portion of the structure is a wall 17 formed of fabric, screen or other suitable material for the purpose of confining liquids to be frozen around the fabricated structure and inhibit excessive currents throughout the structure tending to retard or interfere with the freezing action, and which wall may also serve to protect the frozen body against attrition or wearing away under the action of outside currents to which it might be subjected. This wall will also help to give suitable form to the frozen part.
- 15 In carrying out my invention, a refrigerating element embodying the conduit 15 with the suitable reinforcement 16 and covering wall 17 attached thereto is submerged in the liquid, as shown in Figure 2, whereupon on directing a refrigerating medium through the conduit the liquid in the vicinity of the conduit will be frozen to form a solid body 18, as shown in Figure 3, which is strengthened and reinforced by the conduit and the reinforcing elements and is protected by the wall 17.

Where it is desired to form a wall or body of considerable thickness and density the refrigerating conduit is formed in coils or layers arranged in such proximity to each other that the freezing zones of adjacent conduit portions will overlap so as to freeze the liquid between the conduits. The refrigerating medium may be supplied and caused to flow through the conduit by any suitable refrigerating apparatus located at any convenient point.

In the application of the invention to raising sunken vessels, the freezing element 40 may be employed as a means for closing openings in the vessel's hull, as shown in Figures 4 and 5, or as a means for connecting lifting appliances to the hull or other parts, as shown in Figure 6. Where 45 it is desired to raise a sunken vessel by closing the openings in the hull and pumping out the water to render it buoyant the freezing element is placed over the openings in the hull, such as the ventilators, hatchways, etc., so that when the freezing operations have been effected walls of ice will seal the openings; the walls of ice being formed of such size as occasion may require and reinforced to such extent as to prevent 55 pressures from collapsing the structure while the salvaging is proceeding. Where a vessel has been stowed in, a freezing element may be disposed over the opening 18, as shown in Figure 5, to form an ice patch to temporarily close the opening.

In some instances it may be necessary to dispose freezing elements with reinforcements interiorly of the hull so that the frozen structure will serve to further 60 strengthen the hull. The same system might

be applied to strengthen decks, so that they can withstand strains not expected and provided for in the building of the boat.

Where it is desired to fasten hoisting means to the hull or other parts of the vessel 70 the freezing elements coupled to cables 19 of any suitable hoisting mechanism are arranged at a convenient point on the hull or other parts so that when the liquid adjacent to the element is frozen the solidified 75 mass will adhere to and serve as a connection between the hoisting cables and the hull and parts, as shown in Figure 6. In this application of the invention, the freezing element may be designed to extend substantially throughout the length of the hull 80 so as to provide a large area for cohesion of the ice therewith, or a series of the elements may be used to properly distribute the strains connected with the operation. 85

A similar arrangement is suitable for the recovery of submerged articles of any and all kinds and hoisting or lifting portions of the bottom itself if so desired. It is done simply by lowering a freezing element of 90 any suitable form and strength required, solidifying the liquid surrounding or interpenetrating the parts or particles wanted and lifting the total to a suitable place. Then the freezing medium is shut off and if 95 quick thawing is wanted, it can be accomplished by the blowing of steam or other heating means through the coils.

In the application of the invention, to the construction of coffer-dams and the like, 100 as shown in Figures 7, 8, 9, and 10 inclusive, a fabricated structure of suitable design may be lowered whole or in sections into a body of water so that when the ice is 105 formed around the freezing element a solid wall will be formed, and where the dam is constructed in a running stream it may be fitted with flumes or pipes 20 to allow water to pass through the dam, as is common in coffer-dam construction. In like manner, 110 an ice wall may be formed in a body of water to facilitate the construction of breakwaters, piers, dry docks, and the like.

In the application of the invention to the construction of girders, columns, arches, 115 and structures of various kinds for temporary supports, suitable forms may be provided in which the freezing element is placed so as to freeze water poured into the form to provide a solid structure which may be 120 built up either as a whole or formed of units or sections as occasion may require. Figures 11 and 12 illustrate structures formed in this manner. In this application of the invention, the ice structure may 125 be formed in any desired location, and may be constructed by erecting a reinforcing frame work around refrigerating conduits encased in a suitable housing or form and the liquid to be frozen directed into the 130

form in any suitable manner to build up the ice structure.

In the application of the invention, to damming of subterranean streams, as in mines, tunnels, quarries, and other excavations, as illustrated in Figures 13 and 14, the freezing structure is arranged at a suitable point in the path of the stream and securely anchored against displacement; a wall 22 being provided to form a space 23 rearward of the structure into which concrete or other plastic material may be introduced after the ice wall or patch has been formed so as to effectively seal the outlet of the stream through pipe in any desired manner.

Throughout the various uses to which the invention may be put it is desirable to employ the wall or covering 17 and arranging it to extend over the outer or exposed portion of the ice structure both to confine the body of liquid surrounding the freezing conduit in this way giving the desired form to the frozen parts as well as to protect and strengthen the outer surface of the structure, but in many instances this covering may be dispensed with if so desired. When the liquid that is being solidified is very impure, it is preferable to provide this wall or covering with suitable holes 25 as shown in Fig. 5 so as to allow the concentrated impurities to be displaced with purer liquid by gravity.

By employing my invention a temporary wall or structure may be readily formed in locations which ordinarily are not accessible or are extremely difficult to reach, for example, at great depths in bodies of water, or in swift currents, or in places exposed to winds and wave motion as the refrigerating elements and reinforcing members may be constructed of suitable size and shape in a ship and quickly disposed in the desired position. As the ice structure forms on the refrigerating conduits in outward progression or accumulation, my method of forming a temporary structure as herein set forth affords a convenient means for building a structure on or around irregular bodies, as the frame work and conduits need not be constructed to exactly fit the part to which the structure is to be applied as the ice in building up around the conduits will extend

over and around the surfaces of bodies adjacent thereto and conform itself to all irregularities. This obviates the necessity of 55 constructing the frame work with accuracy.

While I have shown and described several specific embodiments of my invention and illustrated them as applied to several uses, I do not limit myself to the exact 60 details of construction or arrangement of the parts or to the uses shown.

I claim:

1. The method of forming a temporary structure consisting in erecting a reinforcing frame work, incorporating refrigerating conduits in the frame work, directing a refrigerating medium through said conduits, and applying a liquid to said conduits and frame work in such manner as to solidify 70 the liquid to form a frozen body in which the conduits and frame work will be embedded.

2. The method of forming a temporary structure consisting in submerging a refrigerating conduit accompanied by a frame work of reinforcements and a flexible wall in a body of liquid, and directing a refrigerating medium through said conduit to freeze the liquid adjacent the conduit and 80 frame work to form a frozen body reinforced by the frame work and conduits and covered by the wall.

3. A temporary structure comprising refrigerating conduits for solidifying liquids 85 to form a frozen body around said conduits when a refrigerating medium is passed through the conduits, and a flexible wall or limit surrounding the body for protection.

4. A temporary structure comprising refrigerating conduits for solidifying liquids to form a frozen body around said conduits when a refrigerating medium is passed through the conduits, and a flexible wall or limit surrounding the body to shape or form 95 same.

5. A temporary structure comprising refrigerating conduits for solidifying liquids to form a frozen body around said conduits when a refrigerating medium is passed 100 through the conduits, and a wall or limit surrounding the body formed with vents for a limited displacement of impurities.

OSCAR STROMBORG.
